(57) CLAIM

The ornamental design for putter head, as shown and described.

DESCRIPTION

The putter head is to be used as part of a putter-type golf club.

FIG. 1 is a perspective view of a putter head showing my new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof; and,

FIG. 7 is a bottom plan view thereof.

The lower end of a golf club shaft is shown in dashed lines for environmental purposes only and forms no part of the claimed design.
